UNITED STATES PATENT OFFICE.

REINHARD T. TORKELSON, OF WORCESTER, MASSACHUSETTS, ASSIGNOR TO
IVER JOHNSON, OF SAME PLACE.

VELOCIPED.

SPECIFICATION forming part of Letters Patent No. 391,210, dated October 16, 1888.

Application filed May 18, 1888. Serial No. 274,283. (No model.)

To all whom it may concern:

Be it known that I, REINHARD T. TORKELSON, of Worcester, in the county of Worcester and State of Massachusetts, have invented 5 certain new and useful Improvements in Velocipedes; and I do hereby declare that the following is a full, clear, and exact description of the same, reference being had to the accompanying drawings, forming a part of 10 this specification, and in which—

Figure 1 represents a front view of the handle-bar, its handles and bearings, and so much of the fork and head of a bicycle as is necessary to illustrate my improvements. Fig. 2 15 represents upon an enlarged scale a plan of the head, the handle-bar bearings, and a part of the handle-bar. All the following figures are also upon an enlarged scale. Fig. 3 is a central vertical longitudinal section through 20 the handle-bar bearing and part of the handle-bar, looking toward the head. Fig. 4 is a transverse vertical section through the center of the head and handle-bar bearing. Fig. 5 is a plan of one of the handles partly in section, 25 showing my improved construction, whereby said handle may be adjusted and locked on the end of the handle-bar, as hereinafter more fully described; and Fig. 6 is a detached side view of the screw-bolt employed in the construction last above referred to for locking the 30 handle on the bar after adjustment.

My invention relates to improvements in the handle-bar and handle-fastenings of velocipedes, and more particularly to bicycles having 35 what are commonly known as "spade" handles; and it consists of the improved construction hereinafter described, whereby said handle-bar and handle may be adjustably and securely fastened, while at the same time admitting of detachment in an easy and expeditious manner.

In order that others may better understand the nature and purpose of my said invention, I will now proceed to describe it more in detail.

In the drawings, A represents the head of a bicycle, having the bearing A' on the frontside thereof. B is the handle-bar, and C C the handles at the outer ends thereof.

50 The head, with the exception of its bearing A', is made substantially as in other bicycles,

and is provided with the usual center bolt, a, set-nut b, and washer c. The front of said bearing A' is provided with a vertical transverse slot, d, preferably at its center and extending back nearly through to the center bolt, a, as shown in Fig. 4. It is also provided with a longitudinal opening, e, inclined or flaring outward from said transverse slot in opposite directions, as is shown in Fig. 3. The 55 purpose of the slot d is to receive the central detachable operating-head f on bolt g, and of the inclined opening e to receive the inner ends of the handle-bar, which are made beveling or cone-shaped to fit the opening, said 60 handle-bar being made in two parts, instead of extending through its bearing in one piece, as ordinarily.

When the several parts are fitted together for use, the head f occupies a position over 70 the center of the bolt g, as is shown in Fig. 3, and both are made so as to turn together when said head is turned, and also to admit of the insertion of the bolt endwise into said central opening in the head. In this instance the 75 head is made with a square central opening, and the bolt correspondingly shaped at its center to fit the same for said purpose; but I do not limit myself thereto, as many equivalent constructions may be adopted to accomplish 80 the same result.

At each side of the head the bolt g is provided with threads, the thread upon one end being right-handed, and left-handed upon the other end. Said threaded portions are fitted 85 to turn in correspondingly-threaded longitudinal openings in the inner ends of each part of the handle-bar. Therefore when said ends of the handle-bar are inserted in the beveled openings in the bearing and turned up tight 90 over the bolt g it is obvious that the parts will be held in a very firm and rigid manner, and they are locked in said position by means of pins h h, projecting laterally from the handle-bar, which fit in longitudinal slots h' h', formed 95 in the bearing A'. In fastening the two parts of the handle-bar to said bearing A' their inner ends are first turned up over the ends of the central bolt, g, as far as the pins h h will permit without striking the ends of the bearing, said pins being in line with their respective slots, h' h', and the two parts of the handle- 100

bar in their proper positions. By now turning the head *f* the bolt *g* is also turned, thus causing the two sections of the handle-bar to be drawn inward, so that their cone-shaped 5 ends will bear against the flaring or inclined surfaces of opening *e*, the pins *h h* also being at the same time moved forward into their respective holding-slots, thereby fastening and locking the handle-bar in a very secure manner, as previously stated, while at the same time admitting of its being quickly and easily detached for any purpose.

I prefer in practice to make the head *f* in circular form with a series of transverse slots, 15 *i*, in its periphery, as shown in the drawings, whereby it may be conveniently turned; but, if desired, any other suitable shape may be adopted in lieu thereof; or the head may be entirely dispensed with and the bolt *g* turned 20 by fitting an ordinary wrench over the central part thereof.

It is also preferable to employ a separate re-enforcing or strengthening piece of tubing, 25 *j*, or its equivalent at the inner ends of the two sections composing the handle-bar, provided with threaded openings to receive the bolt *g* and fastened to said sections by the pins *h h* and by brazing; but I do not limit myself thereto, as the same forms no essential part of 30 my invention.

Prior to fastening the ends of the handle-bar to bearing *A'*, as previously described, the nut *f* and bolt *g* are fitted in position in said bearing by first slipping the head into the 35 transverse slot *d*, and then passing the bolt *g* endwise through the same up to the center thereof, as shown in Fig. 3.

In practice sufficient space is provided for 40 between the inner ends of the handle-bar and head *f*; also between the pins *h h* and the bottoms of their slots *h' h'*, to take up the wear incident to usage. Although it is preferable to 45 employ the pins and slots *h' h'*, they are not absolutely essential, and may be dispensed with, if desired.

My improvement upon the handle-fastening 50 consists in fitting a short screw-bolt, *k*, in the threaded longitudinal opening *l* in the handle-shank *m*, said screw-bolt being interposed between the outer threaded end, *n*, of the handle-bar and the bottom of said opening. It is 55 provided with a smooth longitudinal hub, *o*, projecting toward the handle, which in this instance fits in a smooth longitudinal opening in the base of the handle-frame, both the hub and said opening being of considerably less diameter than the diameter of the screw-bolt *k*. If preferred, however, the screw-bolt may be made without the hub *o*, and the opening 60 in the handle-shank may be extended through full size. Both ends of the screw-bolt are provided with transverse slots *p p*, or the equivalent thereof, whereby it may be turned. The purpose of said screw-bolt is to lock the 65 handle in any adjusted position on the handle-bar.

In fitting the handle to the handle-bar said handle is first turned up over the threaded end of the handle-bar, and after having been turned up to the proper point and adjusted 70 as desired the screw-bolt is turned up tight against the end of said handle-bar, thus securely locking it in its adjusted position. By said construction it is obvious that by loosening up the screw-bolt the handle may be turned 75 into any desired position convenient to the rider in operating the machine, and then securely locked in said position, as aforesaid.

I am aware of the United States Patent, No. 286,131, to D. S. Hall, dated October 2, 1883, in which is shown an "adjustable check or bearing, *i*," corresponding to the screw-bolt *k*, and therefore make no claim thereto, broadly, but limit my invention to the combination thereof with the velocipede-handle and its 85 shank, as set forth in my third claim.

What I claim as my invention, and desire to secure by Letters Patent, is—

1. In a velocipede, the head thereof having a bearing provided with a central vertical 90 transverse slot, and a longitudinal opening inclined or flaring outward in opposite directions from said transverse slot, in combination with a head fitted in the transverse slot, and a right and left hand screw-bolt fitted in said head, and also in the inner ends of two sections composing the handle-bar, said two sections 95 comprising the handle-bar having threaded openings at their inner ends to receive the screw-bolt aforesaid and beveled to fit the longitudinal inclined opening in the bearing, also having laterally-projecting pins adapted to fit in longitudinal slots in said bearing when the parts are fitted together, substantially as shown and specified.

2. In a velocipede, the head thereof having a bearing provided with a central vertical transverse slot, and a longitudinal opening inclined or flaring outward in opposite directions from said transverse slot, in combination 100 with a head fitted in the transverse slot, and a right and left hand screw-bolt fitted in said head, and also in the inner ends of the two sections composing the handle-bar, said two sections 105 comprising the handle-bar having threaded openings at their inner ends to receive the screw-bolt aforesaid and beveled to fit the longitudinal, inclined, or beveled opening in the bearing when the parts are fitted together, substantially as shown and specified.

3. The combination, with the velocipede handle-shank and frame, having a longitudinal threaded opening and a smooth longitudinal opening, respectively, of the outer threaded end of the handle-bar with a short screw-bolt, having means whereby it may be turned up against the outer end of the handle-bar, substantially as and for the purpose set forth.

REINHARD T. TORKELSON.
